SMOKER'S ASH TRAY

Arnold Starkenberg, New York, N. Y., assignor to Starke Design Inc., Brooklyn, N. Y., a corporation of New York

Application October 17, 1955, Serial No. 38,417

Term of patent 3½ years

(Cl. D85—2)

Fig. 1.

Fig. 3.

Fig. 2.

I claim:

The ornamental design for a smoker's ash tray, substantially as shown.
